UNITED STATES PATENT OFFICE.

JAMES S. RAIRDEN, OF WATERFORD, CALIFORNIA.

FLY SWATTER.

Application filed July 2, 1925. Serial No. 40,984.

To all whom it may concern:

Be it known that I, JAMES S. RAIRDEN, a citizen of the United States, residing at Waterford, county of Stanislaus, State of California, have invented certain new and useful Improvements in Fly Swatters; and I do declare the following to be a full, clear, and exact description of the same, reference being had to the accompanying drawings, 10 and to the characters of reference marked thereon, which form a part of this application.

This invention relates to improvements in fly swatters of the type having a wire 15 mesh swatting element, and particularly represents an improvement over the type of swatter shown in my Patent No. 1,501,- 467, granted me the 15th day of July, 1924.

The principal object of the present invention is to arrange the spring elements by means of which the swatting surface is held in elastic or flexible relation to the handle, in such a manner that the construction and assembly of the parts of the device is 25 rendered much simpler and less expensive without sacrificing anything of efficiency.

A further object is to provide oppositely wound helical spring elements, provided as a single unit and so arranged that no movement or uncoiling of one spring will be had when the other spring is in tension, and vica versa. This increases the life of the 30 springs since they are never strained beyond their normal neutral or slack positions in an uncoiling direction.

These objects I accomplish by means of such structure and relative arrangement of parts as will fully appear by a perusal of the following specification and claims.

40 In the drawings similar characters of reference indicate corresponding parts in the several views:

Fig. 1 is a front view of the swatter.

Fig. 2 is a fragmentary cross-section of 45 the same enlarged.

Fig. 3 is a fragmentary elevation enlarged showing the winding of one of the spring elements on its supporting member.

Referring now more particularly to the 50 characters of reference on the drawings, the numeral 1 denotes the handle of the device, preferably made of stiff wire, and bent in a loop like form with a binding sleeve 2 about its upper end. Above the sleeve the wires forming the handle flare in opposite directions to form arms 3 on the outer ends

of which are upwardly projecting and parallel members 4. These members 4 are connected at their upper ends by a cross member 5. The members 1, 3, 4, and 5 are preferably 60 formed of a single piece of wire, the ends of which are suitably connected and concealed by the sleeve 2. The member 5 of course is circular in cross section, and forms the support and hinge or pivotal rod for the 65 swatting element 6.

This element is in the form of a rectangular piece of wire mesh of suitable size, bent around the member 5 and extending upwardly for a certain distance as at 7. The 70 overlapping or abutting portions of the swatting element are clamped together at suitable intervals by wire clips 8.

Wound about the member 5 adjacent its ends and enclosed by the overlapping portions of the swatting element are helical spring coils 9. The adjacent ends of these coils are connected by a loop 10 which is disposed between the overlapping portions of the wire mesh and extends nearly to the 80 top of said overlap. The outer or opposite ends of the coils are laterally movably and oppositely engaged with the vertical members 4 as shown at 11.

The coils are so wound relative to the loop 85 and their engagement with the members 4 is such that when the loop moves around the rod 5 in one direction, one coil will be wound up or placed in tension while the other coil will not be correspondingly unwound but will remain in its normal slack or neutral position. This is because the portion 11 on said last named spring is then free to move away from the corresponding member 4, since it is not tightly held thereto. 90 A similar but an opposite action is had of course when the loop is swung in the other direction.

This prevents any weakening of the 100 springs due to the constant unwinding action which would otherwise be had. When both springs are in neutral or normal condition, the loop lies parallel to the plane of the handle and the swatting element 6 is of course maintained by said loop in a similar plane.

When manipulating the swatter, only one 105 spring at a time is placed in operation, the other offering no resistance, as above stated. The result is that the element has a very quick snapping action and hence is very effective in catching and striking flies unawares.

From the foregoing description it will be readily seen that I have produced such a device as substantially fulfills the objects of the invention as set forth herein.

5 While this specification sets forth in detail the present and preferred construction of the device, still in practice such deviations from such detail may be resorted to as do not form a departure from the spirit 10 of the invention, as defined by the appended claims.

Having thus described my invention what I claim as new and useful and desire to secure by Letters Patent is:

15 1. A fly swatter including a handle, a rod connected to and extending transversely of the plane of the handle at one end thereof, a swatting element turnably mounted on the rod, oppositely acting helical springs wound in spaced relation about said rod, and a loop member connecting the adjacent ends of the springs and having constant engagement with the swatting element beyond the plane 20 of the rod, to maintain the element in normal predetermined alinement relative to the handle.

20 2. A fly swatter including a handle, a rod connected to and extending transversely of the plane of the handle at one end thereof, a swatting element turnably mounted on the rod, oppositely acting helical springs wound in spaced relation about said rod, a loop member connecting the adjacent ends of the springs and having constant engagement with the swatting element beyond the plane 25 of the rod, to maintain the element in normal predetermined alinement relative to the handle, and means whereby when the loop and element are deflected one way or the other about the rod, only one of said 30 springs will be placed in action.

3. A fly swatter including a handle, a rod connected to and extending transversely of the plane of the handle at one end thereof, a swatting element turnably mounted 45 on the rod, oppositely acting helical springs wound in spaced relation about said rod, a loop member connecting the adjacent ends of the springs and having constant engagement with the swatting element beyond the 50 plane of the rod, to maintain the element in normal predetermined alinement relative to the handle, and means whereby when the loop and element are deflected one way or the other about the rod, one spring will be 55 placed in tension while the other may freely turn on the rod without becoming unwound beyond its normal neutral position.

4. A fly swatter including a handle, a rod connected to and extending transversely 60 of the plane of the handle at one end thereof, a swatting element turnably mounted on the rod, oppositely acting helical springs wound in spaced relation about said rod, a loop member connecting the adjacent ends 65 of the springs and having constant engagement with the swatting element beyond the plane of the rod, to maintain the element in normal predetermined alinement relative to the handle, vertical members fixed with 70 the rod at the ends thereof, and projections formed with the adjacent ends of the springs and engaging the vertical members in opposite and laterally movable manner, and arranged to bear against said members 75 when the corresponding springs are in tension but to move away from said members when the springs are turned beyond their normal slack condition in a direction tending to cause them to unwind.

In testimony whereof I affix my signature.

JAMES S. RAIRDEN.
